[57] **CLAIM**

The ornamental design for a toner cartridge, as shown and described.

DESCRIPTION

FIG. 1 is a left side, top and front perspective view of a toner cartridge showing our new design;

FIG. 2 is a front elevational view thereof;

FIG. 3 is a rear elevational view thereof;

FIG. 4 is a top plan view thereof;

FIG. 5 is a bottom view thereof;

FIG. 6 is a left side elevational view thereof;

FIG. 7 is a right side elevational view thereof; and,

FIG. 8 is a perspective view showing the toner cartridge in a printer.

The broken lines showing a printer in FIG. 8 are for illustrative purposes only and form no part of the claimed design.
